UNITED STATES PATENT OFFICE.

FRANK S. THOMAS, OF TOPEKA, KANSAS.

DESIGN FOR A DESK-CABINET.

SPECIFICATION forming part of Design No. 18,322, dated May 15, 1888.

Application filed March 1, 1888. Serial No. 265,867. Term of patent 14 years.

To all whom it may concern:

Be it known that I, FRANK S. THOMAS, a citizen of the United States, residing at Topeka, in the county of Shawnee and State of Kansas, have invented and produced a new and useful Design for Desks or Cabinets Arranged for the Use of Insurance Agents, of which the following is a specification, reference being had to the accompanying drawings, 10 forming a part thereof.

Figure 1 is a front elevation showing my newly-designed desk or cabinet closed. Fig. 2 is a perspective view illustrating the desk opened for use.

15 The design comprises a base, A, having paneled ends *a* and a top, *a'*, which slightly overhangs the front and ends, as illustrated. The front edges of the ends *a* are finished with vertical moldings *B*, representing columns, the front *A'* of the base *A* being divided by additional vertical moldings, *B'*, similar to the moldings *B* at the extreme ends of the front, and extending horizontally from molding to molding are strips *b*. The spaces between the 20 vertical moldings *B* and *B'* and the horizontal strips *b* are occupied by drawers *b'*, as illustrated.

25 Upon the top *a'* of the base rests an upper case or cabinet, C, the open front of which is closed by a door, *C'*, supported at its lower edge between the end pieces, *c*, of the case by horizontal pivots. The outer face of this door has grooved panels *c'*, separated by a horizontal rail, *c''*, the side stiles thereof being beaded and the top and bottom rails of the door being ornamented, as shown in Fig. 1. The interior of the case is fitted on one side with 30 crossing partitions or divisions *d* and on the

other side with a vertical partition or partitions, *d'*, the space between the partitioned part and the bottom of the case being occupied by drawers *D*, as seen in Fig. 2. Above the partitioned part of the case is an ornamental molding, *E*, horizontally arranged, and extending upward diagonally from the ends of this 40 molding *E* are two similar moldings, *e*, which meet above the center of the case, the three moldings forming a triangular space, which is filled by a panel, *E'*.

The ends of the case are paneled, as shown 50 in Fig. 2.

I claim—

1. The design for desk-cabinets, consisting of a base having its ends closed and its front divided by vertical moldings and horizontal 55 strips, the spaces between said moldings and strips being occupied by drawers, and an upper case closed at the ends and having triangularly-disposed moldings at top, the front open side below said moldings being closed by 60 a paneled door, substantially as described and shown.

2. In a design for a desk-cabinet, an upper case closed at the ends and having in front triangularly-disposed moldings at top, horizontally-arranged drawers at bottom, and the intervening space occupied by vertical and horizontal partitions, substantially as described and shown.

In testimony whereof I affix my signature in 70 presence of two witnesses.

FRANK S. THOMAS.
